ELECTRIC INSULATOR

Harold P. Sleeman, Lisbon, Ohio, assignor to The
R. Thomas & Sons Company, Lisbon, Ohio, a
corporation of Ohio

Application May 24, 1938, Serial No. 209,812

4 Claims. (Cl. 174—140)

This invention relates to electric insulators and more particularly to insulators constructed in a manner tending to eliminate interference with radio and nearby communication lines, due to electro-static discharges.

In high voltage electric apparatus electro-static discharges occur between the metal and the dielectric parts of insulators, as between the metal cap or pin and the porcelain body of some insulators, and between the tie wire or cable and the dielectric body of other insulators. These discharges cause interference with radio reception and with some communication lines.

Heretofore various expedients have been employed in the manufacture of electric insulators for the purpose of eliminating these electro-static discharges but these expedients have all had disadvantages, such as expense of materials and fabrication, difficult processing, insufficient reduction in the amount of discharge and insufficient durability.

It is an object of my invention to provide an improved electric insulator structure which is simple to manufacture and efficient in eliminating electro-static discharges.

Another object is to provide, on critical areas of the insulator, a coating having electrical conduction properties and bonded to the porcelain body, to reduce to a minimum corona and surface discharge effects at the critical areas.

Another object of my invention is to provide a coating of the above type on critical areas of an electric insulator, which coating shall be protected against abrasion, dust and adverse weather and other conditions.

Other objects will become apparent as the invention is described in the accompanying drawing.

In the drawing Fig. 1 is a side elevation view of a pin-type insulator with the right half in section, embodying my invention.

Fig. 2 is a side elevation view of a suspension or strain-type insulator with the right half in section, embodying my invention.

Fig. 3 is a fragmentary section view showing in enlarged detail a portion of the coated area of the insulator in Fig. 1.

Referring to the drawing, the pin-type insulator of Fig. 1 comprises two porcelain shells 10 and 12 having nesting sections with suitably roughened side walls, as by the attachment of finely ground porcelain particles 14 vitrified to the body by means of the surface glaze, and cemented together by cement 16. The head of the upper shell is provided with a transverse

groove 18 for a line wire conductor, and a circumferential groove 20 is provided around the head for the reception of a tie wire which securely fastens the line conductor to the insulator in conventional fashion.

Experience has shown that corona or electro-static discharges are likely to occur at the following areas of the insulator: In the transverse line conductor groove—as indicated by 22 and 22^a; in the circumferential tie wire groove—as indicated by 24; adjacent the periphery of the nesting recess of the upper porcelain shell 10—as indicated by 26; and adjacent the entrance of the supporting pin (not shown) in the lower porcelain shell 12—as indicated at 28. The areas 18, 24, 26, 28 will be understood by those skilled in the art to be surfaces of revolution, while the surfaces 22, 22^a include the whole saddle or line conductor groove. These areas may be generally classed as critical areas for electro-static discharge or corona.

I have found that by applying a preparation of various metallic oxides to the critical areas of the unfired clay body of the insulator and then applying the usual non-conducting silicate glaze 25 27 all over the insulator, and then firing the thus treated insulator, there is formed between the silicate glaze and the porcelain body of the insulator a layer or film 29 of semi-conducting material. This layer is an independent layer not 30 mixed in the glaze or in with the porcelain to any substantial extent, but is, nevertheless, bonded to both. Combinations of metal oxides, which I have used, satisfactorily include those which have long been used in pottery and tile 35 decoration, such as manganese, uranium, chromium, iron and aluminum.

In applying the oxide layer, the preparation in the form of a finely ground powder is mixed to a thin consistency with water containing an attachment vehicle, such as gum arabic and is either painted, dipped or sprayed on the critical areas of the unfired clay body prior to the final glazing operation. The glazing is then accomplished usually by immersing the entire insulator into 45 the liquid silicate glaze. The insulator, when removed from the silicate bath is fired, as usual.

Several important advantages attend the manufacture of insulators with my under-glaze semi-conducting layer, placed as indicated. 50 Among these advantages are:

During firing, the glaze protects the oxide layer and prevents it from burning away or being deleteriously affected, as it would be if not protected.

After firing and during use, the glaze protects the under-glaze oxide layer from abrasion, dirt, dust and adverse weather and other conditions. My insulator structure is therefore more durable than other structures provided with heretofore known means of eliminating interference with radio reception.

The under-glaze layer is not accompanied by objectionable discharges occurring at the edge of the layer, such as have occurred when attempts were made heretofore to place conductive coatings of metal on top of the glaze.

Thus the provision of a semi-conducting layer under the glaze according to my invention results in a radio interference-free insulator structure which is more durable, less expensive, and more effective in eliminating electrostatic discharges than any prior structure for similar purpose.

The invention may also be applied to other types of insulators. As an example, the suspension or strain-type insulator of Figure 2, may be mentioned. In this type the metal cap 30 is cemented to the porcelain shell or insulator body 32, which has a pin-recess 33 for the insulator supporting pin 34 which is cemented in the recess. The critical areas in this type of insulator are adjacent the lower edge of the cap 30, as indicated at 36; and adjacent the mouth of the pin recess 33, as indicated at 38. These areas

are oxide coated and the insulator is treated in the same manner as described in connection with Fig. 1.

The theory of the invention is not exactly known. Nevertheless, the superior functioning of the under-glaze semi-conducting layer has been demonstrated. Obviously, it was not to be expected that the functions of a layer upon the glaze, in contact with the tie wire and line conductor, or other metal parts, would be performed as well or better by a layer under the glaze. The normal expectation would be that the glaze would insulate the oxide layer from the metal parts and therefore the glaze-covered layer would function in less desirable manner than a metal coating over the glaze. However, due apparently to uneven spreading of the oxide

layer and the glaze, certain minute projections of the oxide through the glaze occur. These are or may be engaged by the metal parts or cement in contact with the insulator and thus impart their potential to the whole semi-conducting oxide layer. (In case, however, the glaze should afford unbroken insulation between the oxide coating and the tie wire, line conductor or other metal parts, a slight abrasive operation to remove a small section of the glaze might be employed.) In absence of certainty, I do not limit my invention to such operation or to the foregoing possible theory.

Many modifications within the scope of my invention will occur to those skilled in the art. Therefore I do not limit the invention to the specific embodiments disclosed.

I claim—

1. An electric insulator comprising a porcelain body having an area coated with a metallic oxide and a silicate glaze over said coated area, said layer and said glaze being affixed to said porcelain body by firing.

2. The means for eliminating interference with radio reception in a ceramic electric insulator comprising a silicate glaze on said insulator, a semi-conducting layer of material beneath said silicate glaze at predetermined areas, said glaze and said layer being affixed to said insulator by firing.

3. An electric insulator comprising a porcelain body having an area coated with a mixture of metallic oxides forming a semi-conducting layer of material, a silicate glaze over said coated area, said layer and said glaze being affixed to said porcelain body by firing.

4. In an electric insulator, the means for suppressing electrostatic discharges which tend to interfere with radio reception, comprising a coating of semi-conducting material applied to predetermined areas of the insulator, and a coating of silicate glaze over said coating, said glaze and coating being affixed to the insulator by firing, a portion of said coating being exposed through said glaze in position to contact with metal parts attached to said insulator.

HAROLD P. SLEEMAN.
